UNITED STATES PATENT OFFICE

RUDOLF A. ISENBERG, OF LOS ALTOS, CALIFORNIA

DESIGN FOR A MILK-BOTTLE HOLDER OR ANALOGOUS ARTICLE

Application filed January 14, 1931. Serial No. 38,299. Term of patent 14 years.

To all whom it may concern:

Be it known that I, RUDOLF A. ISENBERG, a citizen of the United States of America, residing at the city of Los Altos, in the county of Santa Clara and State of California, have invented a new, original, and ornamental Design for a Milk-Bottle Holder or Analogous Article, of which the following is a specification, reference being had to the accompanying drawings, forming a part thereof.

Fig. 1 is a front elevation of a milk bottle holder or analogous article;

Fig. 2 is a side elevation of Fig. 1; and
Fig. 3 is a plan view showing my new design.

I claim:

The ornamental design for a milk bottle holder, or analogous article, as shown.

RUDOLF A. ISENBERG.
